Harry C. Schroeder Attorney

of said bars, a projection on each counter engageable for manipulation of the counter, and an abutment portion on each counter adapted to abut against the adjacent counter to hold said projections spaced from one another, when said adjacent counters of a transverse series are turned in the same direction, each of said transverse series of counters being separated into a multiple group, and a separate counter aligned with the group for indicating the total of said transverse row.

3. In an abacus a frame including a plurality of substantially parallel bars, a series of spaced counters frictionally pivoted on each bar, said counters being arranged in series also transversely of said bars, a projection on each counter engageable for manipulation of the counter, and an abutment portion on each counter adapted to abut against the adjacent counter to hold said projections spaced from one another, when said adjacent counters of a transverse series are turned in the same direction, each of said transverse series of counters including a group of four adjacent counters and a fifth spaced from but aligned with said group.

4. In an abacus a frame including a plurality of substantially parallel bars, a series of spaced counters frictionally pivoted on each bar, said counters being arranged in series also transversely of said bars, a projection on each counter engageable for manipulation of the counter, and an abutment portion on each counter adapted to abut against the adjacent counter to hold said projections spaced from one another, when said adjacent counters of a transverse series are turned in the same direction, each of said transverse series of counters being separated into a multiple group, and a separate counter aligned with the group for indicating the total of said transverse row and abutment elements between said group and said separate counter, to locate said separate counter and the adjacent counter of said group in counting position.

5. In an abacus a frame including a plurality of substantially parallel bars, a series of spaced counters frictionally pivoted on each bar, said counters being arranged in series also transversely of said bars, a projection on each counter engageable for manipulation of the counter, and an abutment portion on each counter adapted to abut against the adjacent counter to hold said projections spaced from one another, when said adjacent counters of a transverse series are turned in the same direction, each of said transverse series of counters including a group of four adjacent counters and a fifth spaced from but aligned with said group and abutment elements between said group and said fifth counter to locate said fifth counter and the next adjacent counter of the group in counting position.

6. In an abacus a frame, a plurality of counters, a plurality of pivots supporting said counters in spaced groups, each counter including a hub frictionally held on one of said pivots in a selected position, a tip projection for manipulation, and a body connecting said tip projection to said hub, and an abutment on said body for holding adjacent tip projections spaced.

RALPH E. RICKARD.
